UNITED STATES PATENT OFFICE.

WILLIAM HENRY DINSPERL, OF NEW YORK, N. Y., ASSIGNOR TO ATLAS DEVICES COMPANY, INC., A CORPORATION OF NEW YORK.

PNEUMATIC DISPATCH APPARATUS.

Application filed May 20, 1922. Serial No. 562,447.

To all whom it may concern:

Be it known that I, WILLIAM H. DINSPERL, a citizen of the United States, residing at New York city, in the county of New York, State of New York, have invented certain new and useful Improvements in Pneumatic Dispatch Apparatus; and I do hereby declare the following to be a full, clear, and exact description of the invention, such as 10 will enable others skilled in the art to which it appertains to make and use the same.

This invention relates to pneumatic dispatch tube systems, and has reference more especially to control or power saving devices for controlling and regulating the flow of air through the tube lines of the system both when the lines are empty, that is unoccupied by carriers, and when carriers are in transit through the lines.

20 The invention involves the provision of an improved air control and regulating device of the type which is set forth in the application of Dinspel and Weigle filed August 12th, 1920, Serial No. 403,017, which 25 has matured in Patent No. 1,470,600, granted October 16, 1923. The device may be employed in conjunction with "pressure systems", so called, in which carriers are propelled through the tube line by means of a 30 blast or current of air under pressure, as well as vacuum systems. For the purpose of illustration, the construction and operation of the device will be described in connection with pneumatic dispatch systems operating 35 on the vacuum principle wherein the tube lines are open and a partial flow of air is normally maintained through the line.

In accordance with the invention, there is 40 provided a valve situated in the tube line of a pneumatic dispatch system which is normally maintained open to permit a partial flow of air through the line when unoccupied by carriers. The valve mechanism, as in the 45 valve of the earlier application referred to, includes means which is operable by obstruction of the partial air flow in the line, as when a carrier is inserted in the bell mouth entrance of the line, to increase the opening of the valve and correspondingly the flow 50 of air to propel carriers through the line. In the preferred form of control and regulating device, illustrated and described in the above specified application, the partial flow of air normally maintained through the line, in-

stead of passing direct from the transit line 55 through the suction tube, in which the valve is customarily situated, thence to the suction drum, the partial or fractional air flow is maintained through a by-pass and pilot line, which in turn is connected to the suction 60 drum, and the valve in the tube line is therefore normally closed when a tube line is unoccupied. Upon insertion of a carrier in the line, the valve actuating mechanism operates to open the valve, establishing direct 65 communication between the transit line, or rather the suction tube, and the suction drum and the increased air flow to propel the carrier passes directly from the transit line and the suction tube to the drum.

In the device constituting the present invention, the by-pass and pilot line, through which the partial or fractional flow of air in the earlier form of device is normally maintained, is entirely eliminated by the 75 provision of means, preferably adjustable, such as a set screw, which may be set so as to prevent the valve in the tube line from entirely shutting off communication between the suction tube and the suction drum. Such 80 means may be adjusted so as to normally hold the valve off its seat a greater or less amount, dependent upon the amount of partial or fractional air flow which it is desired to maintain. In this way a partial or 85 fractional flow of air is normally maintained directly through the tube line to the suction drum without a by-pass or shunt line. This results in simplification and cheapening of construction, and in the advantage that the 90 noise caused by air friction through the by-pass or shunt line is eliminated, and greater efficiency of operation of the device and of the system as a whole has been obtained in actual practice.

95 Preferably the mechanism for actuating the valve in the tube line consists of a diaphragm which is operatively connected thereto, the means for normally holding the valve unseated being constructed and arranged to prevent the diaphragm from entirely closing the valve. As in the earlier valve construction set forth in the above specified application, the diaphragm is constructed and arranged to respond to variations in pressure in the tube line, or more specifically the suction tube, in which the device is customarily located, and the dia-

phragm moves the valve toward and away from its seat in accordance with the pressure conditions in the line, usually operating upon a reduction in pressure in the line to open or to increase the opening of the valve, and upon an increase in pressure to close the valve.

In the specific form of construction hereinafter described, the present device like the earlier form, has a valve situated in the line with which a main diaphragm, mounted in a casing is operatively connected, and there is provided an auxiliary diaphragm associated with the main diaphragm and a regulator 15 associated with the auxiliary diaphragm, having a blade or vane situated in the tube line, and which operates at a predetermined rate of flow of air, or amount of kinetic energy of the moving air column to control 20 the action both of the auxiliary and main diaphragms to open and close the main valve. The means for normally preventing the main diaphragm from completely seating the valve consists of a set screw projecting through the main diaphragm casing and providing an abutment for the means, such as a connecting rod, operatively connecting the main diaphragm and valve. The invention is illustrated in the accompanying 25 drawings, in which—

Fig. 1 is a perspective view of the suction end of a tube line,

Fig. 2 is a sectional view illustrating the construction of the valve mechanism making 35 up the control and regulating device,

Fig. 3 is a sectional view showing the connection between the transit line and suction tube,

Fig. 4 is a sectional view of the valve 40 mechanism similar to Fig. 2, but showing the valve in its normally open position, permitting a partial or fractional flow of air through the tube line,

Fig. 5 is a top view of the valve and dia- 45 phragm casings showing a portion of the mechanism enclosed therein,

Fig. 6 is an end view of the valve and dia- 50 phragm casings illustrated in Fig. 5, and

Fig. 7 is a sectional view of the upper part 55 of the diaphragm casing.

The pneumatic dispatch system has a plurality of tube lines consisting of transit lines, each made up of an outgoing or sending tube 7, as from the central station, provided with an open bell mouth 8 and a return tube 9 discharging through a flap or hinged door 10 into a terminal 11, the tube lines 7 and 9 being connected at the out-station by a connection similar to the connection 11 joining the tube 9 with a suction tube 12 to form a continuous line, as is usual. At the out-station there is a flap or door similar to the door 10 for sending carriers, dispatched through the tube 7, back to 60 the central station through the tube 9.

The tube line comprising the sending and receiving tubes is connected through the suction tube 12 with a suction drum 13, the tube 12 being provided with a screen housing 14. Situated in the tube 12, and interposed between the transit line and the suction drum, is the control and regulating device 14. The details of construction of this device are illustrated on an enlarged scale in Figs. 2, 4, 5, 6 and 7, and, since the construction is for the most part the same as that of the preferred form of valve and regulator mechanism illustrated and described in the earlier application filed by me jointly with Edmund Weigle on August 12, 1920, Serial 70 No. 403,017 above noted now Patent No. 1,470,600, granted October 16, 1923, reference may be had to this application for a complete description of the details of construction and operation.

For the purpose of describing the invention of this application, it will suffice to say that the device consists of a globe valve casing 15, integral with a diaphragm casing 16, situated in the suction tube 12 in which the main operating parts of the mechanism are housed, an auxiliary valve casing 17 communicating with the suction tube through a connection 18, and a regulator 19. The globe valve casing 15 has a port or opening 20 in a plane at right angles to the suction tube through which air flows from the transit line to the suction drum. The air flow through the line is controlled by a main valve 21 which, in Fig. 2, is shown in the open position to permit a substantial flow of air through the line for the propulsion of carriers, and in Fig. 4, is shown in its normally slightly open position to permit a partial or fractional flow of air through the line as when the line is unoccupied by carriers. This valve 21 is operatively connected to a main diaphragm 22 by means of a connecting rod 23, the latter being threaded at both ends to receive the valve and the central portion 22a of the diaphragm, and sliding on a rod 24 held in a boss or bearing 25. The boss 25 forms part of a cover plate 26 which closes one side of the globe valve casing and forms an abutment for a coil spring 27 between this plate and the valve 21 which is normally under tension urging the valve to its seated position. The diaphragm 22 is mounted in the casing 16 which is in communication through ports 28 on one side of the diaphragm 22 with the lower part of the suction tube 12 and is adapted to be put in communication with the atmosphere through a port 29 on the other side of the diaphragm. The two 115 chambers 16a and 16b into which the diaphragm casing 16 is divided by the diaphragm 22 are in communication through a by-pass 30 (Fig. 7) and port 31, the extent of opening of which is controlled by a 120

screw needle valve 32. The port 29, or rather the port 33 in the plug 34, through which the port 29 opens to the atmosphere, is opened and closed by means of a valve 35. The valve 35 is connected to an auxiliary diaphragm 36 mounted in the auxiliary valve casing 17, the latter being entirely open to the atmosphere on its lower side through ports 37 on one side of the diaphragm, and communicating on the other side of the diaphragm with the suction tube 12 through the passageway 38 and connection 18. The connection 18 is provided with a needle valve 39 for changing the size of the opening of the passageway 40 in the connection 18. On the upper side of the connection 18 is a port 41 normally closed by a valve 42. The valve 42 is mounted on the end of a lever 43 pivoted at 44 between its ends, and mounted on the opposite end of the lever is a blade or vane 45 situated in the suction tube.

Threaded into the wall of the diaphragm casing 16, adjacent the chamber 16^b, is an adjustable screw 46 having a finger grip 47 by which it may be screwed so that its end will be projected more or less into the interior of the valve casing. The end of this screw forms an abutment for the end of the connecting rod 23, and, as will be seen from an inspection of Fig. 4, when the screw is adjusted so that its end projects into the interior of the valve casing 16, the valve 21 will be held from its seated position, the amount of opening depending of course upon the adjustment of the screw. This small amount of valve opening is normally maintained to permit a partial or fractional flow of air from the transit line to the suction drum directly through the tube when the line is unoccupied by carriers.

The operation will be briefly reviewed although this is fully described in the pending application already referred to. With no carriers in the tube line, the valve 21 and its associated parts and operating mechanisms are in the position illustrated in Fig. 4. The small opening of the valve permits a partial or fractional flow of air through the line. When a carrier is inserted, the free flow of air through the line, under the action of the suction means, is obstructed and the pressure of the air column between the carrier and the suction drum is quickly reduced or, in other words, the suction or partial vacuum is increased. This reduced pressure, or increased partial vacuum, also occurs in the upper part of the auxiliary valve casing 17 above the auxiliary diaphragm 36 by virtue of the connection of the valve casing with the suction tube through the passageway 38 and the passageway 40 in the connection 18. The reduction in pressure or partial vacuum which forms above the diaphragm 36, and the atmos-

pheric pressure through ports 37 existing beneath the diaphragm, causes the latter to rise, occupying the position shown in Fig. 2, and also the valve 35 uncovering the ports 33 and 29. Atmospheric air is thus admitted into the main diaphragm casing 16 in the chamber 16^b on one side of the main diaphragm 22. Atmospheric pressure on this side of the diaphragm with the reduced pressure existing on the other side of the diaphragm, by reason of communication of the chamber 16^a with the suction tube, results in an unbalanced pressure, forcing the diaphragm to the left (Fig. 2), and increasing the opening of the valve 21 against the pressure of the spring 27. This places the transit tube in more or less full communication with the suction drum increasing the suction, the flow of air into the inlet end of the line, and thus the difference in pressure between the air columns on both sides of the carrier, which then furnishes the propelling force to propel the carrier through the line. The full pressure acts to propel the carrier along up-grade or horizontal stretches of the tube line in the case of long lines. When the carrier is travelling through a short line, or strikes a descending grade in a long tube line, however, the speed of the carrier immediately increases to a great extent because of the addition of the force of gravity or the excessive suction in a short line. As soon as the speed of the carrier increases, the rate of flow of the air column in front of the carrier, propelled by the piston action of the carrier, also increases to such an extent that it will exert a force, due to its kinetic energy, on the blade or vane 45 sufficient to depress the lever 43 to the dotted position indicated in Fig. 2, thus raising the valve 42 off its seat and opening the port 41. Atmospheric air rushes through the port 41 and into the upper part of the auxiliary diaphragm casing 17 balancing the pressure in this casing, whereupon the weight of the valve 35 will cause it to again seat closing the port 33. The air confined in the chamber 16^b of the diaphragm casing 16 then exhausts through the passageway 30 into the opposite chamber 16^a on the other side of the diaphragm, and the valve 21, under the combined action of the spring 27 tending to seat the valve, and the continued suction on both sides of the diaphragm through ports 28, gradually moves to the right and comes to rest in the slightly open position when the end of the connecting rod 23 abuts against the end of the adjusting screw 46. In this position, the valve is slightly open an amount depending upon the adjustment of the screw 46 and the valve normally remains in this position, when the line is unoccupied by carriers, to normally maintain a partial or fractional flow of air

through the line compared to the full flow which the suction means is capable of producing through the line with a full open valve setting.

5. I have described above the operation of the blade or vane 45 resulting from the increase in the rate of flow of the air column in front of the carrier, which is brought about by increase in speed of the 10 carrier. Of course, a similar increase in the rate of air flow takes place the instant the carrier is delivered from the line, at which time there is nothing to obstruct the flow of air. And this increase in the rate 15 of air flow resulting from the delivery of a carrier operates through its kinetic energy on the blade or fan 45 in the manner above described to restore the main valve to its normal slightly open position, where it remains until the next carrier is inserted.

I claim:

1. In a pneumatic dispatch system, a tube line, a valve situated in the tube line, means for holding the valve in a normally 25 open position to secure a partial flow of air through the line, mechanism for controlling the operation of the valve, and means, operable, upon insertion of a carrier in the line, to actuate said valve controlling mechanism to increase the flow of 30 air into the inlet end of the tube line to propel the carrier, substantially as described.

2. In a pneumatic dispatch system, a 35 transit line, a suction tube, a valve situated in the suction tube, adjustable means for holding the valve in a normally open position, mechanism for operating the valve, and means, operable upon insertion of a 40 carrier in the line, to control said mechanism whereby to increase the opening of the valve, substantially as described.

3. In a pneumatic dispatch system, a tube line, a valve situated in the tube line 45 which is normally open to secure a partial flow of air through the line, means responsive to the pressure in the line for operating the valve, and a device responsive to the movement of air in the line for controlling the operation of said valve operating means, substantially as described.

4. In a pneumatic dispatch system, a tube line, a valve situated in the tube line which is normally open to secure a partial flow of 55 air through the line, means operable by obstruction of the partial air flow in the line to increase the opening of the valve, and a device responsive to the movement of air in the line for controlling said means, substantially as described.

5. In a pneumatic dispatch system, a transit line including a suction tube, a normally open valve situated in the suction tube for controlling the flow of air through the line, means which is constructed and ar-

ranged to be actuated by an increase in the amount of suction in the line for opening the valve, and a device which is actuated independently of the suction in the line for causing said valve actuating means to operate to partly close the valve when the speed of a carrier in the line becomes excessive, substantially as described.

6. In a pneumatic dispatch system, a transit line including a suction tube a normally open valve situated in the suction tube for controlling the flow of air through the line, means which is constructed and arranged to be actuated by an increase in the amount of suction in the line for opening the valve, and a device, including a blade or vane situated in the suction tube, which is responsive to the movement of air in the line for causing said valve actuating means to operate to partly close the valve when the speed of a carrier in the line becomes excessive, substantially as described.

7. In a pneumatic dispatch system, a tube line, a valve situated in the tube line, a diaphragm casing, a diaphragm within the casing operatively connected to the valve which is constructed and arranged to respond to variations in pressure in the line to move the valve toward and away from its seat, and an adjustable screw in a wall of the casing which is adapted to be set to prevent the diaphragm from completely closing the valve, thereby normally to secure a partial flow of air through the line, substantially as described.

8. In a pneumatic dispatch system, a tube line, a valve situated in the tube line, a main diaphragm operatively connected with the valve, an auxiliary diaphragm associated with the main diaphragm, which is constructed and arranged to respond to the pressure conditions in the line to effect the movement of the main diaphragm, and a set screw for normally preventing the valve, under the action of the main diaphragm, from completely closing the tube line whereby normally to secure a partial flow of air through the line, substantially as described.

9. In a pneumatic dispatch system, a tube line, a normally open valve situated in the tube line, means for holding the valve in the normally open position, a main diaphragm connected with the valve and which is responsive to decrease of pressure in the tube line for increasing the opening of the valve, an auxiliary diaphragm associated with the main diaphragm, and a regulator for controlling the operation of said auxiliary and main diaphragms, including a blade or vane situated in the tube line, which is adapted to be actuated by the movement of the air in the line, substantially as described.

10. In a pneumatic dispatch system, a

tube line, a valve situated in the tube line, a diaphragm casing, a diaphragm within the casing operatively connected to the valve and constructed and arranged to respond to variations in pressure in the line to move the valve toward and away from its seat, and adjustable means adapted positively to prevent the diaphragm from completely closing the valve, thereby normally to secure a partial flow of air through the line, substantially as described.

In testimony whereof I affix my signature.

WILLIAM HENRY DINSPER.
